UNITED STATES PATENT OFFICE.

THOMAS N. MANUEL, OF MILWAUKEE, WISCONSIN, ASSIGNOR TO ALLIS-CHALMERS COMPANY, OF MILWAUKEE, WISCONSIN, A CORPORATION OF NEW JERSEY.

LAGGING.

No. 919,198.

Specification of Letters Patent.

Patented April 20, 1909.

Application filed December 17, 1906. Serial No. 348,169.

To all whom it may concern:

Be it known that I, THOMAS N. MANUEL, a citizen of the United States, residing at Milwaukee, in the county of Milwaukee and State of Wisconsin, have invented a certain new and useful Laggings, of which the following is a specification.

This invention relates to lagging for cylinders or other similar objects, and its object 10 is to provide a neat, cheap arrangement of parts whereby the lagging may be readily secured to the object with the minimum expense for fitting and securing it in place.

In the drawings which accompany this 15 specification and form a part thereof and on which the same reference characters refer to the same elements wherever they appear in each of the several figures and which illustrate an embodiment of this invention as applied to a Corliss type of steam cylinder,— Figure 1 represents a perspective view of a cylinder of the type described with the new and improved lagging secured thereto, the cylinder being ready for the reception of the 20 various parts which are commonly secured thereto. Fig. 2 represents a perspective view of the same cylinder with the parts commonly secured thereto in position. Fig. 25 3 represents a vertical transverse section of the cylinder. Fig. 4 represents a perspective 30 of a fragment of the lagging as it would appear if assembled without the cylinder. Fig. 5 represents a perspective view of a fragment of the band member; and Fig. 6 represents a view of the lagging provided with a reinforcing piece.

In machine shop practice it is customary 35 to provide the cylinders of steam engines and similar apparatus with a cover which serves in some cases merely an ornamental purpose, and in other cases serves to retain heat insulating substance in contact with the object to which the lagging is applied.

If it were commercially practicable in the 40 ordinary manipulations of machine shop work to machine the parts accurately to standard gage, lagging could be prepared according to standard gage and specification which could be accurately assembled with the 45 object in connection with which it is to be used. As, however, in ordinary machine work it is necessary to keep down cost by performing the machine work within the limits of accuracy that are tolerable for the work in hand, it has 50 been found impossible as a practical propo-

sition to prepare lagging which can be assembled with the object which it is to cover without having recourse to a great deal of hand fitting, especially is this the case in engine cylinders of the class illustrated in which 55 considerable time is required to fit the lagging of ordinary forms around the bonnets, etc. of the cylinder.

It was formerly the custom to use an angle iron at the meeting edges of the lagging and 60 inside the lagging to which the edges of the lagging were secured and then to fasten upon the outside of the lagging a band member or covering strip to conceal the joint thus made. With this construction where the 65 angle iron was bent around the bonnets, one web of the iron had to be removed at each bonnet which required a large amount of hand work at the vise to secure a proper fit and to make a reasonably good piece of work. 70

It is the object of this invention to reduce the labor incident to lagging a cylinder or other body to the minimum, and to accomplish this, provision is made whereby the 75 separate sheets forming the lagging may be 80 readily marked off, cut and shaped, placed in position and a binding member applied which firmly binds the sheets together and preferably also to the cylinder or other body to be covered.

Referring to the drawings, 1 designates 85 the barrel of a cylinder of a Corliss engine of usual form; 2 the valve bearing parts; 3 the base; 4 the steam pipe boss; 5 the bonnet bosses; 6 the seat for the wrist plate bracket; 90 7 the cylinder head boss to which are secured respectively the steam pipe 8, the bonnets 9, wrist plate bracket 10, cylinder head 11 and the plates 12.

The sheet of lagging 13 is cut to extend a 95 trifle beyond the square of the cylinder on the top and ends, as clearly shown by Figs. 3, 4 and 6 of the drawings, and a similar plate is cut to fit upon the opposite side of the cylinder or other body and to project 100 beyond the square thereof, in the same manner as the first plate, as clearly shown by Fig. 3 of the drawings. These plates are then apertured to aline with the ports, etc. of the cylinder, for example, and a third 105 sheet 14 is cut of a width to fit between said two side plates and to be bent around the cylinder, as shown. The band member 15, which is provided with a groove 16, is then 110 bent around so as to conform in shape with

the outline of the plate 14 with the groove 16 embracing the projecting edges of the plate 13, one of these band members being provided for each side of the cylinder. This 5 band member is preferably formed, as shown, of an elongated flat rod or plate which can be readily bent to the form of the body which it is intended to cover.

Ordinarily it will be found sufficient to 10 merely screw or otherwise secure this band member to the casting at available points where it is closely adjacent to the main casting proper, as clearly shown by the screws 17 in Figs. 1 and 3.

15 In large sized engines in order that there may be no tendency for the plates to spring apart at points where they are not firmly retained between the band member 15 and an adjacent part of the casting proper, additional 20 means may be employed in the nature of reinforcing pieces, such, for instance, as is illustrated by Fig. 6, in which the numeral 18 designates a piece of angle iron secured to the plate 13 by rivets or screws 19 and to 25 which the band member 15 is secured by screws or the like 20.

What I claim is,—

1. In a steam engine, the combination 30 with a member having parts disposed at an angle each with respect to the other, of a sheet of lagging adapted to cover a part of said member, said sheet of lagging being of the same general surface dimension as said part of said member, a second sheet of lagging of greater dimension than an adjacent 35 part of said member including the thickness of said first mentioned sheet of lagging when applied thereto so that its edge projects beyond said first mentioned sheet, a binding 40 strip provided with a groove adapted to be seated against said first mentioned sheet of lagging with the projecting edge of said second sheet of lagging received within the groove therein, and means for securing said 45 binding strip to said member.

2. In a steam engine, the combination 50 with a member having parts disposed at an angle each with respect to the other, of a sheet of lagging adapted to cover a part of said member, said sheet of lagging being of the same general surface dimension as said part of said member, a second sheet of lagging of greater dimension than an adjacent 55 part of said member including the thickness of said first mentioned sheet of lagging when applied thereto so that its edge projects beyond said first mentioned sheet, a binding strip provided with a groove adapted to be seated against said first mentioned sheet of 60 lagging with the projecting edge of said sec-

ond sheet of lagging received within the groove therein, means for securing said binding strip to said member, and additional means for securing said sheets together.

3. In a steam engine, the combination 65 with a member having surfaces disposed in different planes, two of which surfaces meet at an angle, of sheets of lagging adapted to cover some of said surfaces, said sheets of lagging each being of the 70 same general surface dimension as the part of said member which said sheet of lagging is designed to cover, and another sheet of lagging of greater dimension than the part 75 of the surface of said member which it is designed to cover including the thickness of sheets of lagging applied to adjacent surfaces so that its edge projects beyond said sheets, and a binding strip provided with a groove adapted to receive said projecting 80 edge, said binding strip being adapted to be secured to said member.

4. In a steam engine, the combination 85 with a member having surfaces two of which meet at right angles to each other, of sheets 90 of lagging for covering said member two of which sheets also meet at right angles to each other, one of said two sheets being plane and having an edge extending slightly beyond an edge of the other of said two sheets, a flat 95 binding strip having a groove formed in a side thereof receiving the extending edge of said plane sheet and said strip being bent in the plane of said plane sheet to conform to the shape of the edge of said plane sheet and to lie in contact with the edge of the similarly shaped other sheet, and fastening means for holding said strip in place.

5. In a steam engine, the combination 100 with a member having surfaces two of which meet at right angles to each other, of sheets 105 of lagging for covering said member two of which sheets also meet at right angles to each other, one of said two sheets being plane and having an edge conforming in shape to and extending slightly beyond an edge of the other of said two sheets, a flat binding strip having a groove formed in a side thereof receiving the extending edge of said plane sheet and applied thereto by bending in the 110 plane of said groove and sheet, and means for holding said strip in contact with the edge of said adjacent other sheet.

In testimony whereof, I affix my signature in the presence of two witnesses.

THOMAS N. MANUEL.
